US00D712954S

(12) **United States Design Patent**
Lin

(10) **Patent No.:** US D712,954 S
(45) **Date of Patent:** ** Sep. 9, 2014

(54) **PROJECTOR**

(71) Applicant: **Delta Electronics, Inc.**, Taoyuan Hsien (TW)

(72) Inventor: **Cheng-Yu Lin**, Taoyuan Hsien (TW)

(73) Assignee: **Delta Electronics, Inc.**, Taoyuan Hsien (TW)

(**) Term: **14 Years**

(21) Appl. No.: **29/450,483**

(22) Filed: **Mar. 18, 2013**

(51) LOC (10) Cl. **16-02**

(52) U.S. Cl.

USPC **D16/235**

(58) **Field of Classification Search**

USPC D16/208, 219, 221, 223–231, 234–235; D21/514; 353/115, 119, 122

See application file for complete search history.

(57) **CLAIM**

The ornamental design for a projector, as shown and described.

DESCRIPTION

FIG. 1 is a perspective view of a first embodiment of a projector showing my new design;

FIG. 2 is a front elevation view thereof;

FIG. 3 is another perspective view showing a second embodiment of a projector according to the present design; and,

FIG. 4 is front elevation view thereof.

The broken lines are for the purpose of illustrating portions of the projector and form no part of the claimed design.

1 Claim, 4 Drawing Sheets

FIG. 2

FIG. 4
